UNITED STATES PATENT OFFICE.

ERNEST A. HALL AND GERALD J. LINNROTH, OF TOLEDO, OHIO, ASSIGNEES TO THE HALL MANUFACTURING COMPANY, OF TOLEDO, OHIO, A CORPORATION OF OHIO.

CYLINDER HONE.

Application filed March 25, 1928. Serial No. 97,240.

This invention relates to devices for truing the internal walls of cylinders by a rotary grinding or abrading action, and is particularly intended for use both in connection 5 with new engine cylinders to give them a perfect initial bore and also in connection with used engine cylinders to eliminate tapers and ovals therein resulting from use.

In the use of a tool of this character, for 10 instance in tapered cylinders to remove the taper, a considerable outward pressure of the abrading members against the cylinder wall, usually as much as 150 pounds, is required in order to effect any cutting or abrading action. To obtain proper results, the abrading members must be parallel with the cylinder axis, and are, therefore, out of parallel with the tapered cylinder wall to be trued. The 15 abrading pressure of the hones or abrading members on the cylinder wall is, therefore, exerted at the end of the members which first contact with the cylinder wall, thus tending to spring the members out of true parallelism and preventing accurate work being 20 accomplished.

The object of this invention is the provision of a device of the character described, the construction of which is such as to positively prevent any springing of the abrading 25 members or their carriers out of parallelism with the axis of the cylinder being treated and which permits a cylinder to be trued with a fine degree of accuracy and with an error of not more than one thousandth of 30 an inch out of true.

A further object of the invention is to provide a device of this character which is capable of having its abrading members set at any desired adjustment and to yieldingly 35 maintain such adjustment, and also of having such members set for a predetermined limit of inward of collapsing movements and to have a yielding outward abrading pressure applied thereto, depending on the 40 nature and particular requirements of the work to be performed.

The invention is fully described in the following specification, and while it is capable of embodiment in numerous forms, three 45 only of such embodiments are illustrated in the accompanying drawings, in which,—

Figure 1 is a side elevation of a tool embodying the invention with the spring tension relieved and with a part broken away. 50 Fig. 2 is a central longitudinal section of the

same with parts in full. Figs. 3 and 4 are a cross-section on the lines 3-3 and 4-4, respectively, in Fig. 1 with parts broken away. Fig. 5 is a central longitudinal section of a slightly modified form of the tool 55 with parts in full, and Fig. 6 is a fragmentary central longitudinal section of the tool showing another modification of the adjusting means, the spring in this view being under tension.

Referring to the drawings, 1 designates the tool body, which has a central bore or opening 2 longitudinally therethrough and is provided in equidistantly spaced relation around its outer side with longitudinally apertured bearing bosses 3 extending lengthwise of the body with their apertures parallel to the body axis. In the present instance, the body 1 is substantially rectangular in cross-section and has at each corner an extension forming a bearing boss 3. Each boss 3 has a pivot pin 4 projecting through its aperture, and a carrier 5 for a stone or abrading member 6 is carried by each pin for transverse swinging movements relative 60 to the body. In the present instance, the pins 4 project beyond both ends of the respective bearing bosses and the carriers 5 have arms which engage the pins at the ends of the bosses, these arms being disposed at 65 the ends of the carriers. The abrading members 6 seat in channelled portions of the carriers and are secured therein by set screws 7, as will be understood in the art.

The body 1 is provided at its inner end 70 with a thrust head 8, which is centrally apertured in axial alignment with the aperture 2 through the body, and, in the present instance, is secured to the body by the pivot pins 4, which thread therein. The pins 4 75 are also preferably fixed in the bearing bosses of the body by pins 9 (Fig. 1), or in any other suitable manner, and the thrust head 8 is spaced from the inner end of the body 1 a distance equal to the width of the respective hinge arms of the carriers 5.

A shaft 10 is feathered in the bore 2 of the body 1 to permit it to have axial movements relative thereto and to cause the body to rotate therewith. The shaft 10 at each 80 end of the body 1, and within the limits of the respective ends of the carriers 5, is provided with a cone 11, the outer one of which is removably carried by the shaft to permit its removal preparatory to removing the 85

shaft from or inserting it into the body 1. The removable cone, in the present instance, is threaded on the lower extended end portion of the shaft and is locked in shouldered engagement with the shaft by a nut 12. The two cones 11 face or have their tapers extending in the same direction and are fixed to the shaft against any relative longitudinal movements.

10 Each carrier 5, at the inner side of each end thereof, is provided with a tapered boss or projection 13 which opposes and is complementary to the tapered surface of the adjacent cone 11, so that the inward swinging movements of the carriers relative to the body are stopped by the cones, and axial movements of the shaft 10 and its cones will permit either a further inward movement of the carriers or will cause positive uniform outward movements thereof, depending on the direction of movement of the cones. Upon an upward or inward movement of the outer cone 11, relative to the body 1, it enters a complementary recess 14 provided therefor in the lower end of the body.

15 The shaft 10 extends outwardly through the central aperture in the thrust head 8 and is provided at its outer end in suitable spaced relation to the thrust head with means for attaching it to a motor shaft, drill press spindle or other suitable driving means. The attaching means, in the present instance, is shown as comprising a socket member 15.

20 Threaded on the shaft 10 between the thrust head 8 and attaching means 15 is a hand nut 16 having a stop sleeve 17 projecting from one side thereof toward the thrust head 8 and adapted to have thrust contact at its free end with said head when the nut 16 is turned down for such purpose. When the stop sleeve 17 is turned down with its lower end in engagement with the thrust head 8, it will be apparent that the shaft 10 will be drawn upward relative to the body 1, thereby causing the cones 11 to be set in any desired position of adjustment with respect to the engaging portions 13 of the carriers 5. This provides an unyielding set adjustment for the carriers, so that when 25 operating within a cylinder the device will not grind the cylinder wall to a greater diameter than that for which the stones are set inasmuch as there is no provision in this case for exerting a yielding outward pressure on the carriers to continue the grinding action beyond the point for which the cones are set. A lock nut 18 is provided on the shaft at the outer side of the nut 16 to cooperate therewith to lock it 30 against accidental turning from a set position. A set screw 19 may be used to more securely lock the nuts 16 and 18 together.

In order to provide the tools with means for effecting a continued outward yielding movement of the carriers during an opera-

tion of the tool, where such action is desired, an adjusting nut 20 is threaded on the stop sleeve 17 and a coiled compression spring 21 is interposed between it and the thrust head 8. It is evident that by turning the stop sleeve 17 back from engagement with the thrust head 18, and turning the nut 20 down to tension the spring 21, a yielding pull is exerted on the shaft 10 relative to the holder 1 to cause the cones 11 to exert a yielding outward pressure on the hone carriers from a contracted position permitted by the spring 21. In other words, if the abrading portion of the tool is inserted in a cylinder and the nut 20 then screwed down to compress the spring 21 and cause an outward grinding pressure of the abrading members against the cylinder wall, the grinding action of the tool when rotated will continue until a predetermined amount of stock has been removed. On the other hand, if it is desired to take off only a very small predetermined portion of the cylinder surface, the spring pressure is relieved and the stop sleeve 17 is turned down to effect a positive setting of the cones 11 for the extent of grinding desired.

25 In practice it is desirable when first truing a cylinder to apply the spring expanding action to the abrading members so that the grinding will continue until a predetermined initial portion of the stock has been removed. When the cylinder has been ground in this manner to substantially the diameter desired, the spring tension is relieved and the stop sleeve 17 turned down to give a positive set adjustment to the abrading members so as to surface and accurately true the cylinder after the yielding grinding action.

30 Another feature of this tool which makes it exceedingly accurate in action, consists in the solid bearing provided at both ends of each of the abrading members by the provision of the cones 11 and complementary coacting portions of the carriers at such points. With this arrangement combined with the rigid spacing of the cones and the facing thereof in the same direction, any inward pressure on the abrading members at one end tending to effect a longitudinal movement of the engaged cone, no matter how slight, will be communicated through the shaft to the other cone so that it will have the same movement, thereby preventing any inward springing movement of one end of the abrading members relative to the other. This is a feature which is extremely important in order to maintain a true parallelism at all times of the abrading members and to accomplish accurate work.

35 In the modification shown in Fig. 5 the positive set feature is omitted and the construction is otherwise changed so as to enclose the spring within a housing part. In

this case a tubular member 25 is substituted for the thrust head 8 and has its bore of sufficient size to receive the compression spring 26 between it and the cone carrying shaft, 5 designated 27. An externally threaded sleeve 28 is threaded into the outer end of the member 25 and bears against the outer end of the spring 26, while the inner end thrust of such spring is exerted against the 10 inner cone 29 of the shaft. It is apparent that an adjustment of the spring tension is effected by an inward or outward turning of the sleeve 28. In this form the direction of taper of the cones is reversed over that 15 previously described.

In the modification shown in Fig. 6 both the positive stop and yielding adjustment features are present, as described in connection with the first form, the only difference 20 being that the construction is such that the direction of taper of the cones is reversed and the spring is disposed within an enclosing part of the tool. In lieu of the thrust head 8 of the first form described, the holder 25 is provided at its inner end with a tubular extension sleeve 30 into which is threaded the stop sleeve 31, the lower end of which may be turned into stop engagement with the upper large end of the adjustment cone 30 32. A spring tension adjusting sleeve 33 is threaded into the upper end of the stop sleeve 31 in bearing relation to the cone carrying shaft 34 and has thrust engagement with the upper end of a tension spring 35 that is enclosed within the stop sleeve 31 35 and has its lower end in thrust engagement with the adjacent cone 32.

We wish it understood that our invention is not limited to any specific arrangement, 40 construction or form of the parts, as it is capable of numerous modifications and changes without departing from the spirit of the claims.

Having thus described our invention, what 45 we claim as new and desire to secure by Letters Patent is:

1. In a tool of the class described, a rotatable body, an elongate abrading member carried by the body for outward movements 50 relative to its axis, and drive means movable lengthwise of the body and abrading member and having a fixed portion receiving the inward thrust of the abrading member and, when moved in one direction 55 lengthwise of the abrading member, causing an outward positive adjustment thereof.

2. In a tool of the class described, a body, a rotatable drive means for the body mounted for axial movements relative thereto and 60 having fixedly spaced cam thrust portions, and transversely movable abrading means carried by the body in inward thrust contact with said cam portions whereby an axial movement in one direction of the drive 65 means relative to the body effects a positive

outward movement of the abrading means.

3. In a tool of the class described, a body, a set of elongate abrading-member carriers carried by the body and transversely movable relative thereto, a drive shaft extending 70 through the body for rotating it and permitting it to have axial movements relative to the shaft, and a set of spaced cones tapering in the same direction and fixedly carried by the shaft, said cones having positive outward thrust engagement with the carriers in spaced relation longitudinally thereof, an outward adjustment of the carriers being effected by a movement in one direction of the shaft relative to the body. 80

4. In a holder of the class described, a rotatable body, an elongate abrading-stone carrier parallel to the body axis and carried by the body for transverse movements relative thereto, corresponding tapered portions 85 at each end of the carrier, a shaft engaging the body to drive the same and adapted to have axial movements relative thereto, said shaft having two longitudinally spaced fixed cones of corresponding taper engaging the 90 respective tapers of said carrier to provide a positive inward-thrust receiving means for the carrier ends and to effect a positive outward adjustment of the carrier when the shaft is moved in one direction relative to the body, and adjustable means coacting with the shaft and body to effect a positive predetermined limiting of the movement of the shaft in one direction relative to the body. 95

5. In a holder of the class described, a rotatable body, an elongate abrading-stone carrier parallel to the body axis and carried by the body for transverse movements relative thereto, corresponding tapered portions 105 at each end of the carrier, a shaft engaging the body to drive the same and adapted to have axial movements relative thereto, said shaft having two longitudinally spaced fixed cones of corresponding taper engaging the 110 respective tapers of said carrier to provide a positive inward thrust receiving means for the carrier ends and to effect a positive outward adjustment of the carrier when the shaft is moved in one direction relative to the body, 115 adjustable means coacting with the shaft and body to effect a positive predetermined limiting of the movement of the shaft in one direction relative to the body, and means operable to act on the shaft and body to 120 impart a predetermined yielding movement of one relative to the other and a consequent yielding outward pressure on the carrier.

6. In a tool of the class described, a rotatable body, a shaft for driving said body 125 and capable of limited axial movements relative thereto, a pair of corresponding cones carried in fixed spaced relation by the shaft and facing in the same direction, elongate abrading-stone carriers carried by the body 130

in spaced relation around the same and with their longitudinal axes disposed lengthwise of the shaft, each of said cones having coaction with said carriers, whereby any movement of the shaft in one direction will impart like outward movements to both ends of the carriers, and adjustable tension means acting on the shaft and body for yieldingly opposing a movement of the shaft in one direction relative to the body.

7. In a tool of the class described, a rotatable body, a shaft for driving said body and capable of limited axial movements relative thereto, a pair of corresponding cones carried in fixed spaced relation by the shaft and facing in the same direction, elongate abrading stone carriers carried by the body in spaced relation around the same and with their longitudinal axes disposed lengthwise of the shaft, each of said cones having coaction with said carriers whereby any movement of the shaft in one direction will impart like outward movements to both ends of the carriers, adjustable tension means acting on the shaft and body for yieldingly opposing a movement of the shaft in one direction relative to the body, and adjustable means operable to positively limit to any predetermined extent the movement of the shaft in one direction relative to the body.

8. In a tool of the class described, a body, a plurality of abrading stone holding members carried by the body for swinging movements transversely thereof and each having longitudinally spaced surfaces, a shaft in driving connection with the body and adapted to have limited axial movements relative thereto, said shaft having tapered portions which are fixedly spaced axially thereof and facing in the same direction for coaction with said longitudinally spaced surfaces of the stone holding members, means coacting with the shaft and body for effecting a predetermined positive set adjustment of the shaft and body, and means cooperating with the shaft and body to effect a predetermined yielding adjustment of the shaft and body.

9. In a tool of the class described, a body, a plurality of abrading stone holding members carried by the body for transverse swinging movements relative thereto, said members being disposed lengthwise of their swinging axes and of the body axis, a drive shaft projecting axially through the body in driving engagement therewith and adapted to have limited axial movements relative thereto, said shaft having corresponding conical portions facing in the same direction and in engagement with adjacent portions of each of said members, whereby movement of the shaft in one direction relative to the body will impart corresponding positive outward adjusting movements to both ends of each of said members, and adjustable spring means operable to impart a yielding move-

ment to the shaft relative to the body in a direction to force the said members outwardly from inwardly compressed positions.

10. In a tool of the class described, a body, a plurality of abrading stone holding members carried by the body for transverse movements relative thereto, said members being disposed lengthwise of the body axis, a shaft projecting axially through the body in driving engagement therewith and adapted to have limited axial movement relative thereto, said shaft having corresponding conical portions facing in the same direction and in engagement with adjacent portions of each of said members, whereby movement of the shaft in one direction relative to the body will effect corresponding positive outward adjusting movements to both ends of each of said members, and adjustable spring means capable of being inoperative and being operable to impart a yielding movement to the shaft relative to the body in a direction to force the said members outwardly from inwardly compressed positions, and adjustable positive stop means operable to limit the relative movements of the shaft and body in member collapsing direction and capable of use when the spring pressure means is inoperative.

11. In a tool of the class described, a body, abrading-stone holding members carried by the body to permit expanding and collapsing movements of the stones relative to the body, a shaft projecting through the body and having corresponding conical portions fixedly spaced longitudinally thereof and facing in the same direction, said portions having outward thrust engagement with respective portions of each of said members whereby a movement of the shaft in one direction relative to the body will impart positive outward movements to said members relative to the body, a stop sleeve threaded to one of said body and shaft and operable to provide an adjustable positive stop for the movement of the shaft in one direction relative to the body, a coiled compression spring adapted to have one end thrust against the other of said shaft and body than the one to which said stop sleeve is threaded, and a member threaded to the stop sleeve and adjustable to act on the spring to exert a yielding member expanding movement to the shaft relative to the body or to relieve such action.

12. In a tool of the class described, a rotatable body, abrading-stone holders carried by the body for transverse movements relative thereto, a drive shaft for the body having axial sliding engagement therewith, said shaft having camming coaction with the stone holders to impart outward transverse movements to the holders when the shaft is moved in one direction relative to

the holder, and separate means interposed between the shaft and body, one being operable to effect a positive set adjustment to the shaft relative to the body and the other being adjustable to exert a yielding outward stone holder actuating movement to the shaft.

13. In a tool of the class described, a body, a plurality of abrading-stone holding members carried by the body for transverse swinging movements relative thereto, a shaft projecting axially through the body in driving engagement therewith and adapted to have limited axial movements relative thereto, said shaft having a conical portion in engagement with each of said members whereby a movement of the shaft in one direction relative to the body will impart corresponding positive outward adjusting movements to the members, a stop sleeve threaded to one of said body and shaft and operable to provide an adjustable positive stop for the movement of the shaft in one direction to the body, a coiled compression spring adapted to have one end thrust against the other of said shaft and body than the one to which said stop sleeve is threaded, and a member threaded to the stop sleeve and adjustable to act on the spring to exert a yielding member expanding movement to the shaft relative to the body, or to relieve such action.

14. In a tool of the class described, a body, a plurality of abrading stone-holding members carried by the body for transverse movements relative thereto, a drive-shaft projected axially into the body in driving engagement therewith and adapted to have limited axial movements relative thereto, said shaft and members having coacting portions whereby a movement of the shaft in one direction relative to the body will impart corresponding positive outward adjusting movements to the members, and means carried by the shaft and adjustable relative to the shaft and body to apply a limited positive unyielding expanding pressure to the stone-holding members.

15. In a tool of the class described, a body, a plurality of abrading stone-holding members carried by the body for transverse movements relative thereto, a drive-shaft projected axially into the body in driving engagement therewith and adapted to have

limited axial movements relative thereto, said shaft and members having coacting portions whereby a movement of the shaft in one direction relative to the body will impart corresponding positive outward adjusting movements to the members, and a stop sleeve threaded to one of said body and shaft and adjustable to apply a limited positive unyielding expanding pressure to the stone-holding members.

16. In a tool of the class described, a body, an abrading stone-holder carried by the body for transverse movements relative thereto, means axially movable within the body and having coaction with the stone-holder to effect an outward movement thereof when the means is moved in one direction relative to the body, and means in connection with said first means disposed at one end of said body and operable to provide a positive stop to limit the relative movements of the body and said axially movable means in holder collapsing direction and also operable to provide an adjustable spring means for yieldingly acting on said body and axially movable means to force the stone-holder outward.

17. In a tool of the class described, a rotatable body, a plurality of stone-carrying holders disposed lengthwise of the body and being transversely movable relative to its axis, a member movable axially of the body and extending centrally therein and having cam coaction with the stone-holders whereby a relative movement of the body and member in one direction will impart outward movements in unison to the stone-holders, and means carried by said member at one end of the body and including a spring and a plurality of parts, which parts are adjustable relative to said member and to each other, one part being adjustable to cooperate with the holder and member to apply a limited positive unyielding expanding pressure to the stone-holders, and the other part being adjustable to coact with the spring and with said body and member to apply yielding outward movements to the stone-holders.

In testimony whereof we have hereunto signed this specification.

ERNEST A. HALL.
GERALD J. LINDROTH.
